STOCK AND DIE FOR USE IN SCREWING
METALS

John Dennis Walker, Glasgow, Scotland

Application August 3, 1937, Serial No. 157,093
In Great Britain June 28, 1937

9 Claims. (Cl. 10—123)

This invention relates to stocks and dies for use in screwing metals, and it has for its object certain improvements designed primarily to enable the rapid cutting of screw-threads to vary fine limits of size, the construction and arrangements of the parts moreover, being such that the removal of one set of dies and the substitution of others may be easily and rapidly effected, the tool as a whole being sufficiently strong to withstand the conditions of ordinary use.

10 The die is formed of a plurality of sections carried in a known manner and actuated by a sleeve screwed into the stock, a portion of which sleeve surrounds the die and contacts with the outer ends of the sections thereof, and is of tapered bore, whereby, when the sleeve is screwed in one direction to produce movement of same in an axial direction at a right angle to the plane in which lie said sections, the latter will be moved radially inward.

20 According to the present invention provision is made whereby the dies may be controlled to cut to micrometric dimensions, in combination with means whereby the micrometric adjusting means may be freed from the aforesaid sleeve to enable the latter to be coarsely adjusted to any desired extent, without employing said micrometric adjusting means.

According to one construction, the sleeve is formed in two concentrically arranged superposed relatively revoluble releasably connected parts, one of which is provided with a micrometer device whereby the limit of inward radial movement of the dies may be controlled to produce threads to very fine limits, the arrangement being such that the dies may be opened to free the work or to start the cutting of a thread without disturbing the setting made to control the limit of inward movement of the dies as just above referred to.

40 Preferably means are provided for locking the sleeve in any desired position within the stock.

The invention will now be described with reference to the accompanying drawings, in which:—

45 Fig. 1 is a plan of a stock and die according to this invention.

Fig. 2 is a section taken on line A—B, Fig. 1.

Fig. 3 is a section taken on line C—D, Fig. 2.

50 Fig. 4 is a plan of the underside of the main body portion of the stock frame.

Fig. 5 is a section taken on line E—F, Fig. 1.

Fig. 6 is a side view showing various components removed from the body of said stocks.

55 Referring to the accompanying drawings, I

indicates the main frame or body portion of the stock, which is provided with handles 2, and the central aperture 3 of which frame is screw-threaded to receive a sleeve 4 provided at its upper end with an outwardly extending milled flange 5. The sleeve 4 and flange 5 may be formed integral, but preferably as shown in the drawings the flange 5 is formed upon the edge of a disc 6 which, upon its underside, is recessed to receive a disc 7 having a central opening 8 with which engages an extension 9 surrounding the opening 10 in said disc 6.

Projecting from the edge of disc 6 is a lug 11, which is inclined upwardly with respect to the upper surface of the disc 7, and engages a slot 12 formed in the edge of disc 6. The purpose of this lug will be hereafter more fully explained.

Located upon the inner face of the disc 7 is an annular body 13 having its periphery inclined as shown in the drawings.

The parts 6, 7 and 13 are connected together by means of screws 14 secured at their lower ends to part 13 and passing through discs 6 and 7, nuts 15 upon the outer ends of the screws serving to draw the parts together so that they become, in effect, a solid body.

20 The upper end of the bore of the sleeve 4 is coned as shown at 16, the periphery of the coned annular body 13 engaging said coned surface and when the nuts 15 are tightened connecting 25 the said annular body 13 to said sleeve in a manner such that when the disc 6 is rotated the sleeve 4 will be rotated with it.

When the nuts 15 are slack, the disc 6 and the parts associated therewith may be rotated independently of the sleeve 4.

30 Reference has already been made to the lug 11, the purpose of which is to carry a stop having a micrometer adjustment. The stop comprises a screw 17 having a milled head and sleeve 40 18 such as is commonly provided upon micrometers, said screw engaging a thread formed in a boss 19 projecting laterally from the end of the lug 11, the sleeve 18 being bored to permit the boss 19 to pass therein, also after the manner of the usual micrometer. Both the sleeve and outer surface of the boss may have indications thereon which may indicate the diameter of the thread which will be formed with the dies set in a certain position, or the marking may be purely arbitrary, and bear no direct relationship to the diameter of the thread being cut.

35 A lock-nut 20 is provided for the screw 17.

40 A stop 20a is provided, which is preferably re-

55

movable, which stop contacts with the head of the screw to limit the rotation of the sleeve 4.

By making the connection between the sleeve and its operating means capable of disconnection, it is possible to give a rough initial setting to the parts before they are clamped together by the nuts 15, the micrometer adjustment being then effected so that the parts of the micrometer being locked, repetition work to fixed dimensions is readily possible.

Preferably the height of stop 20a is capable of adjustment, to which end the stop is provided with a screw-thread engaging a threaded hole 21 in the stock, a grub screw 22 being provided to regulate the extent to which the screw on the stop enters the hole.

In order to secure a more rigid connection between the sleeve 4 and its operating means, the engaging coned surfaces of body 13 and the coned surface of the sleeve engaged by said body are milled or roughened as indicated.

The lower portion of the bore of the sleeve 4 is outwardly coned or tapered in a downward direction, as indicated at 23.

25 Riveted to spigots 24 formed upon the lower or countersunk headed ends of screws 25 is a plate 26, shown more clearly in Figs. 2 and 6.

The bolts 25 are provided with plain shanks 27 and the screw-threaded upper ends of these bolts, 30 which extend through the upper face of the stock frame are provided with milled thumb nuts 28, which latter, when screwed down, hold said bolts so that these in turn hold the plate 26 securely in position within the lower face of said frame, 35 which face is suitably recessed at 29 to accommodate said plate.

30 indicates a boss formed upon the inner face of plate 26, said boss being shaped as shown, and being provided with four radial grooves or slots 31, each of which slots extends from the periphery of the boss to the central perforation 32 thereof, and carries a die section the said boss projecting into the sleeve 4, the sections being retained in their slots by the annular projection 45 33 upon the inner end face of the boss.

A disc 34 secured to the inner end of the boss by screws 35 has its inner face provided with an annular channel 36 to receive the projection 33.

37 indicates generally the die which is formed 50 of four sections 38, each of which sections is bevelled at its outer end and is slidably fitted within one of the aforementioned radial slots 31, with its bevelled end contacting with the tapered portion 23 of the sleeve 4, so that, as the latter 55 is screwed downwardly within the stock, it will cause said sections to move radially inward.

Preferably each section is provided at its outer end with a perforation 39, through which is 60 passed a spring 40, the action of which is to push the sections 38 outwards so that their bevelled ends engage the coned inner surface 23 of the sleeve 4.

The spring is gapped as shown, so as to permit the ready removal of the sections.

65 In order that the spring 40 may not prevent the desired inward movement of the sections, the boss 30 is provided with a circumferential groove 41.

Provided in the frame 1, at one side of the 70 sleeve 4, is a perforation 42, bored to permit the passage of a spindle 43, having an enlargement 43a at one end, the inner face of which is curved to the contour of the outer surface of the sleeve 4, and has grooves thereon forming teeth to engage the teeth on the sleeve.

Slidably mounted upon the other part of the said spindle is a sleeve 44, having a face similar to that on part 43a, also shaped to engage the thread on sleeve 4.

The portion of the spindle upon which is slidably mounted the sleeve 44 is screw-threaded and at its outer end is provided with a thumb nut 45, the arrangement being such that when it is desired to clamp the sleeve 4 against rotation, the thumb nut 45 is rotated to draw the members 43a and 44 toward each other and consequently cause them to tightly engage the sleeve and hold it against rotation.

A guide may be provided which is adjustable within such limits as will enable it to grip sizes 15 of metal to be screwed which are within the limits of the capacity of the stocks, and said guide may be in the form shown and which comprises two jaws 47, 48 housed in channels formed in the disc 49, secured in any suitable manner to 20 the lower face of plate 26, as, for example, by means of the screws 49a, Figs. 3 and 4. The screws 49a are tapped into the body 30. The jaws are engaged by screws 50 engaging appropriately curved slots 51 in plate 52, and passing through openings 49b formed longitudinally of the jaws 47 and 48 and indicated by dotted lines in Fig. 4.

By rotating plate 52 in one or other direction, the jaws will be opened or closed in accordance 30 with the size of metal being screwed.

I claim:

1. A stock, an apertured plate carried by said stock, a boss upon the inner face of said plate projecting axially into said stock, a central opening in said boss, radial grooves in said boss, a die section mounted to slide along each of said grooves, a plate bridging said grooves to retain said die sections slidably therein, a sleeve screwed into the said stock, an internally tapered portion forming part of said sleeve, which portion surrounds said die and contacts with the outer ends of the sections thereof, whereby, when said sleeve is screwed in one direction to produce movement of same axially and 45 at a right angle to the plane in which lie said sections, the latter will be moved radially inward, and settable means for ensuring the adjustment of the dies to repeatedly produce a thread of a certain dimension comprising a member revolvably mounted on said sleeve, means adjustably connecting said member to said sleeve, a projection upon said member and means upon the stock engaging said projection.

2. A stock, an apertured plate carried by said stock, a boss upon the inner face of said plate projecting axially into said stock, a central opening in said boss, radial grooves in said boss, a die section mounted to slide along each of said grooves, a plate bridging said grooves to retain 60 said die sections slidably therein, a sleeve screwed into the said stock, an internally tapered portion forming part of said sleeve, which portion surrounds said die and contacts with the outer ends of the sections thereof, whereby, when said sleeve is screwed in one direction to produce movement of same axially and at a right angle to the plane in which lie said sections, the latter 65 will be moved radially inward, and a spring acting upon said die sections to cause their outer ends to bear against the internally tapered portion of the sleeve, and settable means for ensuring the adjustment of the dies to repeatedly produce a thread of a certain dimension comprising a member revolvably mounted on said sleeve, 70 75

means adjustably connecting said member to said sleeve, a projection upon said member and means upon the stock engaging said projection.

3. A stock, an apertured plate carried by said stock, a boss upon the inner face of said plate, projecting axially into said stock, a central opening in said boss, radial grooves or slots in said boss, a die section mounted to slide along each of said grooves, a plate bridging said grooves to retain said die sections slidably therein, a sleeve screwed into said stock, an internally tapered or coned portion disposed at one end of said sleeve, a second and smaller diametered internally tapered or coned portion disposed at the other end of said sleeve, said first coned portion surrounding said die and contacting with the outer ends of the die sections, a spring acting upon said sections to maintain their outer ends in contact with said first coned surface, an annular member, having an outer coned periphery engaging the second coned surface within the sleeve, screws projecting outwardly from one side of said annular member, a centrally perforated disc resting upon the top of the sleeve and perforated for the passage of the screws upon the annular coned body, nuts upon said screws whereby the coned annular body may be caused to tightly engage the coned surface of the sleeve with which it contacts so that when said disc is rotated in one or other direction the die sections will be caused to move in their slots or by slackening the nuts the outer disc may be rotated independently of the annular conical member for purposes of adjustment, and stop means whereby the terminal position of the sleeve may be adjusted.

4. A stock, an apertured plate carried by said stock, a boss upon the inner face of said plate projecting axially into said stock, a central opening in said boss, radial grooves or slots in said boss, a die section mounted to slide along each of said grooves, a plate bridging said grooves to retain said die sections slidably therein, a sleeve screwed into said stock, an internally tapered or coned portion disposed at one end of said sleeve, a second and smaller diametered internally tapered or coned portion disposed at the other end of said sleeve, said first coned portion surrounding said die and contacting with the outer ends of the die sections, a spring acting upon said sections to maintain their outer ends in contact with said first coned surface, an annular member having an outer coned periphery engaging the second coned surface within the sleeve, screws projecting outwardly from one side of said annular member, a centrally apertured disc resting upon the top of the sleeve, perforations in said disc for the passage of the screws just referred to, an upwardly extending radially disposed projection upon said disc, a second centrally apertured disc resting upon said first disc, perforations in said second disc for the passage of the screws in the coned annular body, a peripheral opening in the second disc for the passage of the projection on the first disc, nuts upon said screws whereby the coned annular body may be caused to tightly engage the coned surface of the sleeve with which it contacts so that when said disc is rotated in one or other direction the die sections will be caused to move in their slots, or by slackening the nuts the outer disc may be rotated independently of the annular conical member for purposes of adjustment, and stop means whereby the terminal position of the sleeve may be adjusted, said stop means comprising a screw passing through

the said projection of the second disc at a right angle to said projection, a head at one end of said screw, a lock nut on said screw, and a projection on the stock adapted to engage the head of the screw and so limit the rotary movement of the sleeve. 5

5. A stock, an apertured plate carried by said stock, a boss upon the inner face of said plate projecting axially into said stock, said boss having a central opening and radial grooves or slots located therein, a die carried by said stock, said die comprising a plurality of sections mounted to slide along said radial grooves or slots, said sliding action causing said die sections to move radially within said stock, a plate bridging said grooves to retain said die sections slidably therein, a sleeve screwed into said stock, an internally tapered portion forming part of said sleeve which surrounds said die and contacts with the outer ends of the sections thereof, whereby, when said sleeve is screwed in one direction to produce movement of same axially and at a right angle to the plane in which lie said sections, the latter will be moved radially inward, means for ensuring the adjustment of the dies to repeatedly produce a thread of a certain dimension, and means for locking the sleeve against rotation, said locking means comprising a screw disposed at a right angle to the axis of the sleeve, an enlargement upon said screw at one end, a curved surface upon said enlargement, grooves upon said surface adapted to engage the threads upon the sleeve, a sleeve slidably mounted upon the shank of the screw also provided with a surface adapted to engage the threads of the die carrying sleeve, a nut upon said screw engaging the outer end of the sleeve to enable the locking elements to tightly engage the die carrying sleeve to prevent its rotation. 20

6. A stock, an apertured plate carried by said stock, a boss upon the inner face of said plate projecting axially into said stock, a central opening in said boss, radial grooves or slots in said boss, a die section mounted to slide along each of said grooves, a plate bridging said grooves to retain said die sections slidably therein, a sleeve screwed into said stock, an internally tapered or coned portion disposed at one end of said sleeve, a second and smaller diametered internally tapered or coned portion disposed at the other end of said sleeve, said first coned portion surrounding said die and contacting with the outer ends of the die sections, a spring acting upon said sections to maintain their outer ends in contact with said first coned surface, an annular member, having an outer coned periphery engaging the second coned surface within the sleeve, screws projecting outwardly from one side of said annular member, a centrally perforated disc resting upon the top of the sleeve and perforated for the passage of the screws upon the annular coned body, nuts upon said screws whereby the coned annular body may be caused to tightly engage the coned surface of the sleeve with which it contacts so that when said disc is rotated in one or other direction the die sections will be caused to move in their slots, or by slackening the nuts, the outer disc may be rotated independently of the annular conical member for purposes of adjustment, and stop means whereby the terminal position of the sleeve may be adjusted, and means for locking the sleeve against rotation comprising a screw disposed at a right angle to the axis of the sleeve, an enlargement upon said screw at 25

30

- one end, a curved surface upon said enlargement, 5
grooves upon said surface adapted to engage the
threads upon the sleeve, a sleeve slidably mounted
upon the shank of the screw also provided with a
surface adapted to engage the threads of the die
carrying sleeve, a nut upon said screw engaging
the outer end of the sleeve to enable the locking
elements to tightly engage the die carrying sleeve
to prevent its rotation.
- 10 7. A stock, an apertured plate carried by said
stock, a boss upon the inner face of said plate
projecting axially into said stock, a central opening
in said boss, radial grooves or slots in said
boss, a die section mounted to slide along each
15 of said grooves, a plate bridging said grooves to
retain said die sections slidably therein, a sleeve
screwed into said stock, an internally tapered or
coned portion disposed at one end of said sleeve,
a second and smaller diametered internally
20 tapered or coned portion disposed at the other
end of said sleeve, said first coned portion sur-
rounding said die and contacting with the outer
ends of the die sections, a spring acting upon said
sections to maintain their outer ends in contact
25 with said first coned surface, an annular mem-
ber having an outer coned periphery engaging
the second coned surface within the sleeve, screws
projecting outwardly from one side of said annular
member, a centrally apertured disc resting
30 upon the top of the sleeve, perforations in said
disc for the passage of the screws just referred
to, an upwardly extending radially disposed pro-
jection upon said disc, a second centrally aper-
tured disc resting upon said first disc, perfora-
35 tions in said second disc for the passage of the
screws in the coned annular body, a peripheral
opening in the second disc for the passage of
the projection on the first disc, nuts upon said
screws whereby the coned annular body may be
40 caused to tightly engage the coned surface of
the sleeve with which it contacts so that when
said disc is rotated in one or other direction the
die sections will be caused to move in their slots
or by slackening the nuts the outer disc may be ro-
45 tated independently of the annular conical mem-
ber for purposes of adjustment, and stop means
whereby the terminal position of the sleeve may
be adjusted, said stop means comprising a screw
passing through the said projection of the second
50 disc at a right angle to said projection, a head at
one end of said screw, a lock nut on said screw,
and a projection on the stock adapted to engage
the head of the screw and so limit the rotary
movement of the sleeve, and means for locking
55 the sleeve against rotation comprising a screw
disposed at a right angle to the axis of the sleeve,
an enlargement upon said screw at one end, a
curved surface upon said enlargement, grooves
upon said surface adapted to engage the threads
60 upon the sleeve, a sleeve slidably mounted upon
the shank of the screw also provided with a sur-
face adapted to engage the threads of the die
carrying sleeve, a nut upon said screw engaging
the outer end of the sleeve to enable the locking
65

elements to tightly engage the die carrying sleeve
to prevent its rotation.

8. A stock, an apertured plate carried by said
stock, a boss upon the inner face of said plate
projecting axially into said stock, said boss hav-
ing a central opening and radial grooves or slots
located therein, a die carried by said stock, said
die comprising a plurality of sections mounted
to slide along said radial grooves or slots and
adapted to move radially with respect to the 10
axis of formation of the thread, a sleeve screwed
into said stock, an internally tapered or coned
portion forming part of said sleeve, said portion
contacting the outer ends of said die sections,
whereby, when said sleeve is screwed in one di-
rection to produce movement of same axially
and at a right angle to the plane in which said
sections lie, the latter will be moved radially
inwardly, a stop for said sleeve, comprising at
15 least two parts, one of which is adjustable, and
whereby said stop, in addition to being adapted
to limit the movement of said sleeve and con-
sequently the radial movement of the die sec-
tions, permits said sleeve to be finely adjusted
20 with respect to the limit imposed by said stop;
and a member carrying one of the parts of said
stop, and rotatably mounted with respect to said
sleeve, to thereby permit the latter to be coarsely
adjusted to any desired extent, without the use
25 of or being subject to the limitation imposable
by the stop; together with means for rigidly con-
necting said member to the sleeve to render the
stop operative.

9. A stock, an apertured plate carried by said
stock, a boss upon the inner face of said plate
projecting axially into said stock, said boss hav-
ing a central opening and radial grooves or slots
located therein, a die carried by said stock, said
die comprising a plurality of sections mounted
to slide along said radial grooves or slots and
adapted to move radially with respect to the axis
of formation of the thread, a sleeve screwed into
35 said stock, an internally tapered or coned por-
tion forming part of said sleeve, said portion
contacting the outer ends of said die sections,
whereby, when said sleeve is screwed in one di-
rection to produce movement of same axially and
40 at a right angle to the plane in which said sec-
tions lie, the latter will be moved radially in-
wardly, a stop for said sleeve comprising at least
45 two parts, one of which is adjustable, and where-
by said stop, in addition to being adapted to
limit the movement of said sleeve and conse-
quently the radial movement of the die sections,
permits said sleeve to be finely adjusted with
50 respect to the limit imposed by said stop; and
a member carrying the adjustable part of said
stop and rotatably mounted with respect to said
sleeve, to thereby permit the latter to be coarsely
adjusted to any desired extent, without the use
55 of or being subject to the limitation imposable
by the stop; together with means for rigidly con-
necting said member to the sleeve to render the
stop operative.

JOHN DENNIS WALKER. 65
